UNITED STATES PATENT OFFICE

171,894

AIRPLANE

Alvin R. Johns, Orrstown, Pa.

Application October 17, 1952, Serial No. 21,873

Term of patent 14 years

(Cl. D71--1)

To all whom it may concern:

Be it known that I, Alvin R. Johns, a citizen of the United States, residing at Orrstown, in the State of Pennsylvania, have invented a new, original, and ornamental Design for an Airplane, of which the following is a specification, reference being had to the accompanying drawing, forming a part hereof.

Figure 1 is a top plan view of an airplane embodying my new design;

Figure 2 is a front elevation thereof; and

Figure 3 is a side elevation thereof.

I claim:

The ornamental design for an airplane, as shown.
